AMPLIFYING APPARATUS

Richard M. Somers, Orange, N. J., assignor to
Thomas A. Edison, Incorporated, West Orange,
N. J., a corporation of New Jersey

Application January 16, 1932. Serial No. 587,120

3 Claims. (Cl. 179—171)

This invention relates to amplifying apparatus and more particularly to an audio amplifier adapted and arranged to be used with commercial types of dictating machines which are provided with electrical recording and reproducing apparatus, and the invention herein disclosed relates more particularly to the mechanical arrangement and construction of the amplifier chassis or frame work.

10 It is an object of this invention to provide an amplifier chassis which shall be neat and compact in appearance and in which access may easily be had to all of the working parts of the amplifier in order to examine and test the 15 same.

It is a further object of this invention to provide an amplifier chassis in which all of the apparatus which is least likely to get out of order is placed on one side of the panel, whereas 20 apparatus more likely to get out of order is placed on the other side of the panel, and in which all wiring is concentrated on one side of the panel.

It is a further object of my invention to provide apparatus of the class described which will fit readily into the space available in the usual type of dictating machine.

Still other objects and advantages of my invention will be apparent from the specification.

30 The features of novelty which I believe to be characteristic of my invention are set forth with particularity in the appended claims. My invention itself, however, both as to its fundamental principles and as to its particular embodiments will be best understood by reference to the specification and accompanying drawing, in which

Fig. 1 is a top plan view of an amplifier chassis according to my invention;

40 Fig. 2 is an end elevation thereof, partly in section, and

Fig. 3 is a side elevation looking toward the right in Fig. 2.

The structural foundation of the chassis according to my invention is provided by the panel 1, which is preferably rectangular and of considerably greater height than width. The panel 1 is provided with flanges 2 on the sides thereof which serve the purpose of reinforcing 50 and strengthening it.

Mounted on the panel 1 on the side opposite the flanges I provide the various elements of the amplifying system which are least likely to get out of order, such, for instance, as the transformers, the power supply filters, chokes and

the like, and in general all of the bulky apparatus designated generally by the numeral 4 in the drawing. All of this apparatus is provided with terminal lugs on the side which is fitted against the panel 1 and the panel 1 is 60 provided with appropriate openings 14 and 15 et cetera, through which the terminal lugs on the apparatus project. Mounted upon the panel 1 on the side opposite the transformer and associated apparatus 4 I provide a plurality of 65 tube shelves 7, 8 and 9. These tube shelves may be in the form of metal plates having down turned flanges similar in construction to the construction of panel 1 with flanges 2, and the shelves are secured against the panel 1 in such 70 a manner that they project horizontally therefrom and are arranged one above the other. The tube sockets such as 10 and 11 are mounted on the shelves 7, 8 and 9 in such a way that the tubes stand with their axes vertically upon the shelves 7, 8 and 9.

Connections are made from the tube sockets to the terminals of the various circuit devices mounted on the panel 1 and additional connections may be made between the terminals 80 themselves. Only a few of such connections are shown in the drawing. It is understood that these connections may merely consist of wires such as connections 18 and 18' and/or they may include resistors 16, 19 and 19' and/or condensers 20 and 20'. The resistors 16, 19 and 19', condensers 20 and 20', and other miscellaneous apparatus such as the fuse block 17, are preferably mounted upon the shelf side of panel 1, as shown.

90 The wiring from the tube sockets is preferably maintained entirely within the flanges on the shelves 7, 8 and 9 so that cover plates may be placed upon the bottom of these shelves to enclose the wiring, and preferably an additional 95 cover plate provided with openings for permitting its passage over tube shelves 7, 8 and 9 is also provided which encloses and protects the wiring on the shelf side of the panel 1. Thus it will be seen that in making inspection or test, 100 it is only necessary to remove the cover plates, whereupon the entire amplifier and all its apparatus is available for test from the shelf side of the panel 1. Preferably the chassis is installed in a cabinet with the apparatus 4 toward the rear of the cabinet and the shelf side of the panel 1 toward the door of the cabinet, from which it will be seen that when the door is closed no apparatus can be seen. When the door is open the only apparatus which is seen 105 110

consists of the tube shelves 7, 8 and 9 with the tubes mounted thereon. However, if it is desired to check the amplifier circuit it is only necessary to remove the tubes from their sockets 5 and to remove the cover plates, whereupon all of the apparatus is available for test, including the apparatus 4 on the opposite side of the panel.

While I have shown and described certain 10 preferred embodiments of my invention, it will be apparent that modifications and changes may be made without departing from the spirit and scope of my invention, as will be understood by those skilled in the art.

15 I claim:

1. In an amplifier, in combination, a vertical panel having flanges on one side, a plurality of circuit devices mounted on the unflanged side of said panel, said devices being connected with 20 terminals projecting through said panel, a plurality of tube shelves secured to the flanged side of said panel and extending horizontally therefrom, said shelves having tube sockets, and connections between said tube sockets and said terminals, said connections all being on the flanged side of said panel and within said flanges.

2. In an amplifier, in combination, a vertical panel having flanges on one side, a plurality of enclosures containing circuit devices and mounted 30 on the unflanged side of said panel, said devices being connected with terminals project-

ing through said panel, a plurality of tube shelves mounted on the flanged side of said panel and extending horizontally therefrom, tube sockets mounted on said shelves, connections between said tube sockets and said terminals, all of said connections being arranged on the flanged side of said panel and within said flanges, and a removable cover plate cooperating with the flanged side of said panel to form an enclosure, said plate providing for the application and removal thereof over said tube shelves.

3. In an amplifier, in combination, a vertical panel having flanges on one side, a plurality of enclosures containing circuit devices and mounted on the unflanged side of said panel, said devices being connected with terminals projecting through said panel, a plurality of tube shelves mounted on the flanged side of said panel and extending horizontally therefrom, each of said shelves comprising a flanged member and cover cooperating to form an enclosure, said shelves having tube sockets, connections extending between said sockets and said terminals, said connections all being on the flanged side of said panel and within the flanges thereof, and a removable cover plate cooperating with the flanged side of said panel to form an enclosure, said cover plate having openings providing for the application and removal thereof over said tube shelves.
